UNITED STATES PATENT OFFICE.

LUDGER E. LA BRIE, OF SOUTH BEND, INDIANA, ASSIGNOR TO BENDIX BRAKE COMPANY, OF CHICAGO, ILLINOIS, A CORPORATION OF ILLINOIS.

SHOE FOR BRAKES.

Application filed June 10, 1928. Serial No. 114,914.

This invention relates to brake shoes and is illustrated as embodied in novel shoes for an internal expanding automobile brake. An object of the invention is to form a very rigid trussed shoe construction permitting the use of pressed sheet metal of relatively light gauge. In one desirable arrangement the shoe comprises two sections, each including a stiffening portion forming half the stiffening web of the shoe and integrally connected at the outer side edge of the friction face of the shoe with a cylindrical flange forming part of the friction face, the two sections being arranged face to face and secured together, preferably with the two cylindrical flanges engaging each other edge to edge. I prefer, in making the heavier shoes to include a reinforcing member between the two stiffening portions of the above-described sections and engaging the inner face of the cylindrical flanges, this member being of channel section when it is desired to provide spaced stiffening webs which may straddle part of an adjacent shoe. To get the utmost rigidity, the portions of the stampings connecting the stiffening portions may be inclined and diverged from each other to give a shoe construction generally of triangular section, i. e. the shoe body is hollow, with the stiffening portions forming the sides of the hollow body.

Other features of the invention relate to novel means of securing spaced pivot bearings for the shoes, and to the formation of novel seats for the lining rivets, and to other novel and desirable constructions which will be apparent from the following description of the illustrative embodiments shown in the accompanying drawings, in which:

Figure 1 is a vertical section through the brake just inside the head of the brake drum and showing the brake shoes in side elevation;

Figure 2 is a partial section on the line 2-2 of Figure 1 showing the overlapped anchored ends of two of the shoes;

Figure 3 is a partial section on the line 3-3 of Figure 1 and showing the pivotal connection between two of the shoes;

Figure 4 is a section through one of the end shoes on the line 4-4 of Figure 1;

Figure 5 is a section through the central shoe on the line 5-5 of Figure 1; and

Figure 6 is a section through an end shoe corresponding to Figure 4 but showing a modified construction.

The particular brake illustrated in Figure 1 includes a rotatable drum 10 at the open side of which there may be arranged a backing plate 12 or other suitable support and within which are three brake shoes 14, 16, and 18, the shoes 14 and 18 preferably being identical and interchangeable. The shoe 16 is generally channel-shaped in section, having two stiffening webs spaced apart from each other and at opposite ends of the shoe arranged to straddle the ends of shoes 14 and 18. Shoe 16 is anchored on the backing plate by being mounted on a pivot 20 carried by the backing plate and passing through a relatively large opening 22 in the stiffening web of the shoe 14. Shoes 14 and 18 are pivotally connected to the shoe 16 by pivots 24 and 26, the pivot 26 being shown with a relatively large spacing portion or head 28 slidably engaging the backing plate 12 and the pivot 24 being shown grooved at one end to interlock with a grooved eccentric stop 30.

The brake may be applied by suitable means such as a double cam 32 arranged to force shoes 14 and 18 in opposite directions against the resistance of a return spring 34, the shoe 16 being applied by shoes 14 and 18 (particularly the latter) against the resistance of an auxiliary return spring 36.

The present invention has to do with the construction of shoes suitable for use in a brake of the type described above or in any equivalent brake. The shoes 14 and 18 are each illustrated as made up of two stampings, which are similar except that the one is the reverse of the other (that is, the one stamping is the mirror image of the other) and each of which includes a cylindrical flange 40 and a radial stiffening portion or web 42 integrally connected with the flange 40 along the side edge of the friction face of the shoe by a connecting portion 44 which is preferably inclined in such a manner that the portions 44 of the two shoe sections diverge from each other to give a hollow shoe section illustrated as being substantially triangular in form. Where the utmost strength is required, a separate reinforcing member such as a plate 46 may be arranged between

the flanges 42 and crossing the hollow section formed by the diverging portions 44 and engaging the inner faces of the flanges 40, which are shown arranged edge to edge 5 with a joint over the edge of the plate 46 and extending lengthwise of the shoe. The inclined portions 44 are pressed down at intervals toward the inside surfaces of the flanges 40 for the lining rivets or other 10 fastenings 48.

The central shoe 16 is of the same general construction as that described above except that the reinforcing member is in the form of a curved channel 50 arranged between the 15 webs 142 to form two spaced stiffening webs and having the bottom of the channel projecting across the joint between the two flanges 40 supporting the brake lining 52 and arranged edge to edge as described 20 above.

If preferred, and as shown in Figure 6, the stiffening member 46 may be omitted and the cylindrical flanges 240 and 241 of the two stampings arranged in overlapping relation- 25 ship instead of in engagement edge to edge.

The inclined bracing portion 44 in Figure 6 will be pressed down at intervals for the lining rivets 48 the same as for the shoes 14 and 18.

30 It will be observed that this type of shoe may be regarded as built up of two separately-formed concave parts facing toward each other and secured together by inner and outer joints extending lengthwise of the 35 shoe.

In order to provide a firm support on the pivots 20, 24, and 26, I prefer to form the stiffening webs of the shoes as made up by the above-described stiffening portions or 40 webs with openings sleeved on the pivots, and dished washers 54 welded to the sides of the stiffening webs, thus giving a pair of spaced bearings for the pivot at each of the 45 points where one of the pivots passes through one of the stiffening webs.

While several illustrative shoe constructions have been described in detail, it is not my intention to limit the scope of the invention to those particular constructions or 50 otherwise than by the terms of the appended claims.

I claim:

1. A brake shoe comprising two separately-formed parts, each having a cylindrical flange integrally continued along one edge to form a stiffening portion offset toward the central plane of the shoe, and which are arranged facing each other with said edges forming the opposite side edges of the shoe. 60

2. A brake shoe comprising two separately-formed parts, each having a cylindrical flange integrally continued along one edge to form a stiffening portion arranged at its inner edge centrally of the shoe, and which are arranged facing each other with said edges

forming the opposite side edges of the shoe, the cylindrical flanges and the opposite stiffening portions forming a hollow shoe body.

3. A brake shoe comprising two separately-formed parts, each having a cylindrical flange integrally continued along one edge to form a stiffening portion offset toward the central plane of the shoe, and which are arranged facing each other with said edges forming the opposite side edges of the shoe, the stiffening portions being secured together to stiffen and reinforce the shoe.

4. A brake shoe comprising two separately-formed parts, each having a cylindrical flange integrally continued along one edge to form a stiffening portion between the edges of the shoe and an inclined bracing portion connecting the flange and said portion and which are arranged facing each other with said edges forming the opposite side edges of the shoe, together with means securing the stiffening portions together to form a stiffening web projecting inwardly of the shoe.

5. A brake shoe comprising two symmetrical parts, each having a cylindrical flange integrally continued along one edge to form a stiffening portion between the edges of the shoe, and which are secured together facing each other with said edges forming the opposite side edges of the shoe.

6. A brake shoe comprising two parts, each having a cylindrical flange integrally continued along one edge to form a stiffening portion between the edges of the shoe, and which are secured together facing each other with the cylindrical flanges edge to edge.

7. A brake shoe comprising two separately-formed parts, each having a cylindrical flange forming at least part of the lining-carrying portion of the shoe and continued at one edge to form an integral stiffening portion, the two parts being secured together facing each other and with said edges forming the opposite side edges of the shoe, in combination with a stiffening part between and secured to said stiffening portions and engaging the inside of said lining-carrying portion.

8. A brake shoe comprising two separately-formed parts, each having a cylindrical flange forming at least part of the lining-carrying portion of the shoe and continued at one edge to form an integral stiffening portion and an inclined portion integrally connecting the flange and said portion, the two parts being secured together, facing each other and with said edges forming the opposite side edges of the shoe, in combination with a stiffening part between and secured to said stiffening portions and engaging the inside of said lining-carrying portion and crossing the space defined by the diverging inclined portions of said parts.

9. A brake shoe comprising two separately-formed parts, each having a cylindrical flange and a stiffening portion integrally connected therewith along one edge, the two parts being secured together with the cylindrical flanges edge to edge, in combination with a stiffening part between and secured to the stiffening portions and engaging the inside surface formed by the cylindrical flanges. 70
10. A brake shoe comprising two separately-formed parts, each having a cylindrical flange and a stiffening portion integrally connected therewith along one edge, the two parts being secured together with the cylindrical flanges edge to edge, in combination with a stiffening part between and secured to the stiffening portions and engaging the inside surface formed by the cylindrical flanges substantially at the joint between the two cylindrical flanges. 75
11. A brake shoe comprising two separately-formed parts, each having a cylindrical flange and a stiffening portion integrally connected therewith along one edge, together with an inclined bracing portion connecting the flange and the stiffening portion, the two parts being secured together with the cylindrical flanges edge to edge, in combination with a stiffening part between and secured to the stiffening portions and engaging the inside surface formed by the cylindrical flanges and crossing the space defined by said inclined bracing portions. 80
12. A brake shoe comprising two parts, each having a cylindrical flange and a stiffening portion integrally connected therewith along one outer side edge of the shoe, and a curved plate engaging the inside of the cylindrical shoe portion formed by the cylindrical flanges, the two stiffening portions being displaced into engagement with opposite sides of said plate and secured thereto. 85
13. A brake shoe having a plane flange formed with an opening to be mounted on a pivot, in combination with a dished washer secured thereto in a manner to be mounted on said pivot and to form with the wall of said opening a pair of spaced pivot bearings. 90
14. A brake shoe having a plane stiffening web formed with an opening to be mounted on a pivot, in combination with a pair of oppositely dished washers secured thereto on opposite sides in a manner to be mounted on said pivot and to form with the wall of said opening three spaced pivot bearings. 95
15. A brake shoe having a plane stiffening web formed with an opening to be mounted on a pivot, in combination with a pair of oppositely dished washers secured thereto on opposite sides in a manner to be mounted on said pivot and to form a pair of spaced pivot bearings. 100
16. A brake shoe comprising a pair of overlapping shoes, one having a pair of spaced webs, and the other having a stiffening web straddled by said spaced webs and having secured on its opposite sides a pair of oppositely dished washers engaging the inner faces of said spaced webs. 105
17. A hollow brake shoe including two separately-formed concave and outwardly-cylindrical members facing toward each other and secured together by inner and outer joints extending lengthwise of the shoe, each of said members providing a part of the friction face of the shoe. 110
18. A hollow brake shoe including two separately-formed concave and outwardly-cylindrical members facing toward each other and secured together by inner and outer joints extending lengthwise of the shoe, the outer joint being arranged substantially in the center of the friction face of the shoe. 115
19. A hollow brake shoe including two separately-formed concave and outwardly-cylindrical members arranged with their concave faces toward each other, and each of which members forms the part of the shoe on its side of the central plane of the shoe, and which members are secured together by joints extending lengthwise of the shoe. 120
20. A hollow brake shoe including two separately-formed concave members, each with a cylindrical flange and a stiffening portion, and which are secured together with their concave faces toward each other and with the stiffening portions secured together and with said flanges secured edge to edge. 125
21. A hollow brake shoe including two separately-formed concave members, each with a cylindrical flange and a stiffening portion, and which are secured together with their concave faces toward each other and with the stiffening portions secured together and with said flanges secured edge to edge, together with a reinforcing member secured between said concave members. 130
22. A hollow brake shoe including two separately-formed concave members, at least one being outwardly-cylindrical and each having a stiffening portion, and which are secured together with their concave faces toward each other and with the stiffening portions secured together. 135
23. A hollow brake shoe including two separately-formed concave members, each with a cylindrical flange and a stiffening portion, and which are secured together with their concave faces toward each other and with the stiffening portions secured together and with said flanges secured edge to edge, together with a reinforcing member secured between said concave members, the stiffening portions being depressed toward the cylindrical flanges at intervals to form seats for lining fastenings. 140
24. A two piece hollow brake shoe with a cylindrical outer friction face with a joint down its center, and having its hollow body 145

depressed at intervals, along both sides of the shoe, toward the friction face, to form seats for lining rivets.

25. A hollow brake shoe with a cylindrical outer friction face comprising two separately-formed flanges arranged edge to edge, friction lining overlying said face, and fastenings for said lining passing through said flanges and having heads within the outline 10 of the hollow shoe.

26. A hollow brake shoe including two separately-formed concave members, each

with a cylindrical flange and a stiffening portion, and which are secured together with their concave faces toward each other and 15 with the stiffening portions secured together and with said flanges secured edge to edge, friction lining overlying said flanges, and fastenings for the lining passing through the flanges and terminating within the out- 20 line of the hollow shoe.

In testimony whereof, I have hereunto signed my name.

LUDGER E. LA BRIE.
